UNITED STATES PATENT OFFICE.

SAMUEL T. STITES, OF ROCKFORD, ILLINOIS, ASSIGNOR TO BURSON MANUFACTURING COMPANY, OF ROCKFORD, ILLINOIS, A CORPORATION OF ILLINOIS.

KNITTING-MACHINE.

1,159,429.

Specification of Letters Patent.

Patented Nov. 9, 1915.

Application filed May 10, 1915. Serial No. 27,204.

To all whom it may concern:

Be it known that I, SAMUEL T. STITES, a citizen of the United States, residing at Rockford, in the county of Winnebago and State of Illinois, have invented certain new and useful Improvements in Knitting-Machines, of which the following is a specification.

This invention relates in general to knitting machines of the "parallel row" type and has more particular reference to the means for adjusting and holding in operative position the reciprocable cam-bars which project and retract the presser-hooks.

In this type of knitting machine, it is necessary mainly because of the wearing of the contacting surfaces between the cam-bars and presser-hooks, to frequently adjust the cam-bars so that presser-hooks will be accurately and uniformly projected to function properly in the knitting operation.

The adjusting means heretofore employed for effecting adjustment of the cam-bars have been so constructed that great difficulty is experienced in securing and maintaining the fine adjustments necessary to keep the presser-hooks working properly. Since unreliable operation of the presser-hooks is inimical to perfect knitting, it is obviously desirable to utilize means whereby the presser-hooks may be easily and accurately adjusted so as to control the extent of projection of the hooks to a fine degree of precision.

One of the primary objects of my invention, therefore, is to provide improved means for adjusting the cam-bars which project and retract the presser-hooks, by which fine and accurate adjustments and alterations of the presser-hooks, may be readily and easily secured and maintained to thereby promote and insure the efficiency of the knitting machine.

Another object of my invention is to provide improved means for adjusting the cam-bars which will yieldingly and continuously hold the same in operation.

Other objects and attendant advantages of the invention will be apparent as the same becomes better understood by reference to the following description, when consid-

ered in connection with the accompanying drawings; wherein—

Figure 1 is an end view of a parallel row knitting machine showing my improvements embodied therein; Fig. 2 is a vertical sectional view through one of the needle beds, illustrating the connection of a cam-bar with a presser-hook; Fig. 3 is a side view of the adjustable guides that coöperate with one cam-bar, the ends of the needle bed being designated by dotted lines; and Figs. 4 to 7 inclusive, show in perspective in disassociated relation the principal parts of the adjustable guide means.

My improvements are applicable to knitting machines of the general type shown in Patent No. 616,600, granted Dec. 27, 1898, to W. W. Burson, and on the drawing herein, I have illustrated merely in outline an end view of a knitting machine of this type, since the relation thereto and the mode of operation of my improvements will be readily apparent to one skilled in the art.

The knitting machine parts shown, comprise the needle beds 5, the needle-operating cam-slides 6, the presser-hook supporting-beds or segments 7, the presser-hooks 8, the cam-bars 9 which project and retract the presser-hooks, the bars 11 serving to hold the presser-hooks down in place, and the bars 12 coöperating with and forming ways for the cam-bars 9 and cam slides 6. The cam-bars 9 are provided with the usual cam grooves 13 which receive the radial lugs of the presser-hooks so that upon lengthwise reciprocation of the cam-bars, the presser-hooks are projected and retracted as is well understood in this art. The cam-bars 9, while guided between the members 7 and 12, are capable of movement laterally between said members so as to change the extent of projection of the presser-hooks, and are adjustably held against lateral movement and maintained in operative position by adjustable guide means mounted on each end of the needle beds.

Since the means for guiding each cam-bar at each end of the needle bed (with an exception to be noted hereinafter) are similar, a detailed description of the guiding means at one end of a needle bed will suffice for an

understanding of my invention. A plate designated in general by reference character 14, slidably associated with one end of a needle bed and having its upper end turned outwardly at right angles to the end face of the needle bed forming a ledge 15, is so positioned with respect to a cam-bar 9 that the face 16 thereof rests upon the top face of the ledge 15 and is guided thereby. Means for 5 adjustably securing said plate 14 to the needle bed in such manner that the plate may be adjusted to move the cam-bar side- 10 wise or laterally between the members 7 and 12, are constructed as follows. A second 15 plate designated in general by reference character 17, positioned on the outer face of the plate 14 is connected to the needle bed by means of pins 18 fixed to the bed and extending outwardly therefrom through 20 elongated openings 19 in the plate 14 and into closely fitting apertures 21 in plate 17. The apertures 19 extending in a plane at right angles to the ledge 15, permit the plate 14 to be moved in the plane of said aper- 25 tures, on the pins 18. The plate 17 while being held against longitudinal movement, is movable on pins 18 toward and away from the needle bed and may be clamped, together with the plate 14, rigidly to the bed 30 by means of a set screw 22 which passes through an aperture 23 in plate 17, an elongated aperture 24 in plate 14 and is threaded into the needle bed. An adjusting member 25, threaded at one end into a tapped 35 opening 20 in the ledge 15, is held at its opposite end against longitudinal movement by engagement of an annular groove 27 formed on the head of the screw 25 with the bifurcated end of a lateral extension 26 40 formed on the plate 17, as shown. The knurled face and the slotted end of the screw member 25 afford adequate provision whereby said screw member may be easily turned. As will be seen in Fig. 2, the guide means 45 at one end only of the machine is provided with means resiliently holding the cam-bar 9 upon the ledge 15. This retaining means comprises an L-shaped plate 28 embracing two adjoining sides 31 and 32 of the cam-bar, provided with a tongue passing through a slot 34 in the ledge 15, the tongue having fixedly secured thereto a guide member 35 which has an upturned end 36 slidably engaging the outer face of the plate 17. An 50 expansion spring 37 coiled about the tongue 33, and interposed between the ledge 15 and the guide member 35 exerts its tension on the retaining plate to constantly 55 urge the cam-bar against the ledge. An auxiliary guide 38 secured to the top of the ledge 15 engages the back of the retaining member to hold it against displacement. 60 From the foregoing, it will be apparent that by loosening the set screw 22 and then 65 turning the screw member 25, which is held

against longitudinal movement by the plate 17, a finely accurate lateral adjustment of the cam-bar may be made. When the desired adjustment has thus been secured, the set screw may be tightened to clamp the 70 plates fixedly to the needle bed. It will be understood, of course, that by lateral adjustment of the cam-bar, the extent of projection of the presser-hooks is changed; and by the use of improved guiding and adjusting 75 means, the cam-bars may be readily and accurately adjusted and then set in adjusted position (by tightening the set screw) without disturbing the adjustments.

I claim:

1. In a knitting machine, the combination with the presser-hooks and reciprocable cam-bar coöperating therewith for projecting and retracting the same, of a movable device upon which the cam-bar slides, a screw 80 adjustment connecting said device with a stationary element of the machine to positively adjust said device with respect to said stationary element, whereby to adjust through the cam-bar the extent of projection of said presser-hooks, and means mounted on said movable device for yieldingly holding the cam-bar in slidable engagement with said device.

2. In a knitting machine, the combination of a frame, a member mounted to reciprocate with respect thereto, a plate slidably associated with the frame and provided with means engaging the said slidable member for guiding the same and provided also with elongated apertures therethrough, a second plate associated with the first named plate and provided with means extending through said apertures and secured to the frame so that the first named plate may be moved with respect thereto, said means including a set screw whereby the two plates may be secured rigidly to the frame, and a screw connection between the plates constructed to permit adjustment of the first named plate, and consequently the reciprocable bar, with respect to the frame.

3. The combination of a stationary element, a member slidable with respect thereto, a plate movable with respect to said stationary element and having a laterally extending portion serving as a guide upon which said member is slidable, means mounted on said lateral portion and constructed to resiliently hold the slidable member in engagement therewith, a second plate associated with the first named plate and secured to the stationary element, a screw connection between the stationary plate and the lateral portion of the movable plate whereby the latter, and consequently the slidable member, may be adjusted with respect to the stationary element, and means for clamping said plates fixedly to the stationary element.

4. In a knitting machine, the combination with the presser-hooks and the reciprocable cam-bar coöperating therewith for projecting and retracting the same, of means upon which the cam-bar slides for holding the same in operative position, including a device movably mounted on a stationary element of the machine and provided with means for adjusting the device with respect to said stationary element to change the extent of projection of the presser-hooks and for fixedly securing the device in adjusted position, and provided also with means yieldingly urging the cam-bar to engagement with the first named means.

SAMUEL T. STITES.
